UNITED STATES PATENT OFFICE.

DAVID T. WILLIAMS, OF PATERSON, NEW JERSEY, ASSIGNOR TO VACUUM ENGINEERING COMPANY, OF NEW YORK, N. Y., A CORPORATION OF NEW YORK.

PNEUMATIC SUCTION-PUMP.

No. 921,040.

Specification of Letters Patent. Patented May 11, 1909.

Application filed October 17, 1908. Serial No. 458,151.

To all whom it may concern:

Be it known that I, DAVID T. WILLIAMS, a British subject, residing at Paterson, in the county of Passaic, State of New Jersey, have ⁵ invented certain new and useful Improvements in Pneumatic Suction-Pumps, of which the following is a full, clear, and complete disclosure.

The object of my invention is to produce a ¹⁰ suction pump, and one particularly adapted to be used in connection with vacuum or pneumatic cleaning systems, which shall be simple in construction, efficient in operation, and one in which the expense of manufacture ¹⁵ is considerably reduced.

In pneumatic cleaning systems heretofore in operation it has been necessary either to completely separate the dust and dirt from the air before passing the air through an ordinary ²⁰ suction pump, by means of dry separators and wet separators, or in other words by passing the air through a chamber in which the main portion of the dust and dirt may collect, and then by removing the remainder ²⁵ of the dust and dirt by absorption in some suitable liquid. On the other hand, when the dust and dirt are passed directly through the suction pump with the water supplied to the saturation chamber, it has been usual to ³⁰ provide a pump of special construction having protecting surfaces, such as by lining the inner surface of the cylinder with brass or similar material.

By the use of the device comprising this ³⁵ invention, I am enabled to use a pump for producing an air vacuum through which air alone passes, thereby eliminating the use of a brass or other lining. In addition to the pump for producing an air vacuum, I ⁴⁰ use an auxiliary pump connected with the chamber through which the air or air and water withdrawn from the cleaning implements passes. This pump connects with the chamber containing the water or other liquid for absorbing the dust and dirt at the ⁴⁵ level at which it is desired to maintain such liquid. This auxiliary pump for the water may be of the well known plunger or displacement type in which the piston enters the piston chamber through a stuffing box, which may be adjusted as occasion requires. The fact that the water containing the dust and dirt is withdrawn from the absorbing ⁵⁰ or saturating chamber by a separate pump, enables this water to be utilized for cooling

purposes in the air pump, which is an important advantage, in view of the double function served by the auxiliary water pump.

For a detailed description of one form of my invention which I at present deem preferable, reference may be had to the following specification and the accompanying drawings forming a part thereof, in which—

Figure 1 is a side elevation of a pump embodying the improvements which are the ⁶⁰ subject-matter of this invention, and Fig. 2 is a vertical sectional view of the same taken substantially upon the line A A.

The numeral 1 indicates the cylinder of the pump, and the numeral 2 the ends thereof which contain valve chambers and suitable water jackets for the cylinder heads and valve chambers.

The numeral 3 indicates the auxiliary water pump of the plunger or displacement ⁷⁰ type, and having the piston or plunger 4 entering the pump chamber 3 through the usual stuffing box 5.

The numeral 6 indicates the absorbing or saturating chamber having a central outlet ⁸⁰ conduit 7 connecting with the air-pump cylinder 1 at its central portion, as indicated in Fig. 1. The chamber 6 is provided with a suitable baffle-plate or plates such as indicated by the numeral 8, and also with a float valve 9 which is connected with the water inlet pipe 10 so that a constant level of the water is maintained. The inlet pipe 11 for the saturating chamber enters the casing of the saturating chamber at its upper portion, ⁹⁰ and the interior of the chamber is provided with means for causing air to flow beneath the surface of the liquid and through the baffle-plates therein, such as by the use of the partition 12. The pipe 13, which enters ⁹⁵ the chamber 6 at the level of the water therein, connects with the pump 3 through which the water passes, being then forced through the pipe 14 and the branches 15 and 16 into the water jackets contained in the ¹⁰⁰ heads 2 of the pump cylinder 1. At points in the cylinder heads separate from the ends of the branches 15 and 16 I introduce outlet pipes 17 and 18 which may pass to any suitable discharge receptacle, such as a sewer or ¹⁰⁵ drain.

The air suction pump is preferably of the horizontal type having valved outlets in the cylinder heads and an inlet pipe communicating with the central portion of the cylin- ¹¹⁰

der, so that the piston which occupies substantially one half of the volume or interior of the cylinder may be covered and uncovered by the piston and act as a valve. However I do not wish to be understood as being limited to the use of this particular type of air pump.

10 The auxiliary water pump 3 may be operated in any suitable manner, such as by connection with an eccentric 19 on the driving shaft 20 of the main air pump.

15 In operation it will be seen that the air containing the dirt, or the dirt, air and water, when the scrubbing process is used, from the vacuum cleaning implements, passes through the screw pipe or conduit 11 into the saturating chamber 6. The air leaves this chamber through the conduit 7, passing through the pump cylinder 1, whence it is discharged into the atmosphere, or into any suitable receptacle or muffler (not shown) by a pipe 21. The chamber 6 being filled with water or other liquid up to the level of the end of the pipe 3 absorbs the dust drawn through the same by the main air pump, thereby causing the dust and dirt to become deposited in said chamber. The water in the chamber being continually agitated by the passage of the air, prevents the dirt from settling to the bottom, and the dirt is therefore thoroughly dissolved and drawn off with the water through pipe 13, its level being maintained sufficiently high through the action of the float valve 9 to cause a constant renewing of the water. 30 This water, after passing through the pump cylinder 3 enters the water jackets of the cylinder heads, thereby keeping them cool and counteracting the effect of the compression of the air being driven out of the cylinder of the air pump.

40 Having thus described this form of my invention, I do not wish to be understood as being limited to the exact details of form and arrangement of parts set forth, for various changes may be made by those skilled in the

art without departing from the spirit and scope of my invention.

What I claim and desire to protect by Letters Patent is:

1. In a pneumatic cleaning apparatus, an air pump, a water pump, an absorbing chamber, a conduit leading from the upper portion of said absorbing chamber to said air pump, and a conduit leading from a point above the bottom of said absorbing chamber but below the end of the first-named conduit, to said water pump.

2. In a pneumatic cleaning apparatus, an air pump, an independent water pump, an absorbing chamber, means for supplying water to the absorbing chamber, said air-pump being connected with said absorbing chamber at a point above the level of the liquid therein, and the water pump being connected with said absorbing chamber at the level of the liquid therein.

3. In a pneumatic cleaning apparatus, an air-pump having cooling jackets, an independent water pump, an absorbing chamber, said air-pump being connected with said absorbing chamber to withdraw air therefrom and said water pump being connected with said absorbing chamber to withdraw water therefrom, the outlet of said water pump being connected with said cooling jackets.

4. In a pneumatic cleaning apparatus, the combination of a double acting air pump, a water pump of the plunger or displacement type, and an absorbing chamber, said air pump being connected with said absorbing chamber at a point above the level of the liquid therein, and the water pump being connected to said absorbing chamber adjacent the level of the liquid therein.

Signed this 15th day of October, 1908.

DAVID T. WILLIAMS.
